UNITED STATES PATENT OFFICE.

WILLIAM G. HOUSKEEPER, OF WILKINSBURG, PENNSYLVANIA, ASSIGNOR TO WESTINGHOUSE ELECTRIC & MANUFACTURING COMPANY, A CORPORATION OF PENNSYLVANIA.

ARC-LAMP.

No. 917,867.

Specification of Letters Patent. Patented April 13, 1909.

Application filed July 9, 1906. Serial No. 325,314.

To all whom it may concern:

Be it known that I, WILLIAM G. Houskeeper, a citizen of the United States, and a resident of Wilkinsburg, in the county of Allegheny and State of Pennsylvania, have invented a new and useful Improvement in Arc-Lamps of which the following is a specification.

My invention relates to arc lamps, and particularly to those in which one or both electrodes contain insulating oxids or compounds.

The object of my invention is to provide simple and effective means for insuring ready establishment of the arcs in lamps of the character indicated.

One or both electrodes of arc lamps are frequently composed of the magnetic oxid of iron, which is a conductor, and the oxids of titanium and chromium, which are insulators when cold, the former being employed to give desirable color characteristics to the arc, and the latter to increase the life of the electrodes. In the operation of such lamps, insulating fumes, composed principally of the non-conducting oxids, occasionally condense and deposit upon parts of the electrodes, and insulating or high resistance slags often form upon the electrodes, good electrical contact between the electrodes being thereby prevented and ready establishment of an arc interfered with.

According to the present application, I propose to cause the electrodes to move rapidly into and out of engagement until the fumes or the slag are removed or until a sufficiently good electrical contact between the electrodes is effected to enable establishment of the arc.

Figure 1 of the accompanying drawings is a view in perspective of a device that may be applied to an arc lamp to enable it to operate in accordance with my invention, and Fig. 2 is a diagrammatic view of the circuits of an arc lamp to which the invention is applied.

Electrodes 1 and 2 of an arc lamp, either or both of which may be composed of the oxids above specified or of other suitable materials, are normally maintained out of engagement by means of a clutch 3. The clutch is adapted to be operated by means of a rod 4, the upper end of which is secured to a movable magnetizable core 5 of an

electro-magnet winding 6, the core 5 being normally supported in its uppermost position by means of a spring 7. The electro-magnet winding 6 is arranged in series with a suitable resistance 8 between one terminal 9 of the lamp and a stationary contact terminal 10, an adjacent stationary contact terminal 11 being connected to terminal 12, of the lamp. Contact terminals 10 and 11 are adapted to be connected by means of either the one or the other of two movable switch members 13 and 14, the latter of which is normally out of engagement therewith. The switch member 13 is provided with an operating magnet winding 15 that is connected between the electrode 1 and the terminal 12 of the lamp and serves to raise the switch member 13 out of engagement with the contact terminals 10 and 11, when the electrodes 1 and 2 are in electrical contact or when an arc exists between them. The switch member 14 is provided with an operating magnet winding 16 that has its terminals connected to the electrodes 1 and 2 and serves to move the switch member 14 into engagement with the contact terminals 10 and 11 when the difference in potential between the electrodes 1 and 2 rises above a predetermined limiting value.

The electro-magnet winding 6 is adapted to be shunted by means of a device that comprises a stationary contact terminal 17 and a movable terminal 18 upon the lower end of a rod 19 that is mounted so as to be capable of a reciprocating motion in guides 20 and 21. The main portion of the rod 19 is screw-threaded for the reception of nuts 22 and 23 that serve as stops, lock nuts 24 being provided for the purpose of securing the stops in position. In order that the rod 19 may be maintained in any position to which it may be moved, it may be pressed firmly against the guides by means of a spring that is interposed between the upper end thereof and a stationary post 26, or any other suitable means may be employed. The portion of the rod 19 between the stop nuts 22 and 23 is embraced by the forked ends of two arms 28 and 29. The arm 28 is secured to the movable magnetizable core 5, and the arm 29, which is more flexible than the arm 28, is secured thereto.

When current is first supplied to the lamp, it traverses the resistance 8, electro-magnet winding 6, and switch member 13, 110

which occupies the position shown in Fig. 2. Energizing of the electro-magnet winding 6 causes the core 5 to be drawn downward in opposition to the tension of the spring 7 and the electrode 1 is thus caused to engage the electrode 2. If the ends of the electrodes are wholly or partially covered with a high resistance slag or with insulating deposits that are formed during 10 operation of the lamp, the resistance of the contact may be so great as to prevent establishment of an arc. However, movement of the magnet core 5 downward also causes the contact terminal 18 to engage the terminal 17, and the electro-magnet winding 6 is thereby shunted and the core 5 and the clutch 3 are drawn upward by the spring 7. The upward movement of the core 5 and the arm 29 that is carried thereby causes disengagement of the terminals 17 and 18 and the electro-magnet winding 6 again becomes energized. Energizing of the winding 6 again causes downward movement of the core 5, and the electrodes will be caused to 15 engage again, and the electrodes 1 and 2 will be moved into and out of engagement with each other in rapid succession until a low resistance electrical contact between them is effected. A circuit is then established from the terminal 9 through electrodes 2 and 1 and operating magnet winding 15 for the switch member 14, thereupon the latter becomes disengaged from the stationary terminals 10 and 11. The circuit of 20 the electro-magnet winding 6 is thereby interrupted and the electrodes 1 and 2 are then separated and an arc established. The lamp will continue to operate until the difference in potential between the electrodes 25 1 and 2 exceeds the predetermined limiting value at which the magnet winding 16 becomes sufficiently energized to cause movement of the switch member 14 into engagement with stationary contact terminals 10 and 11. The circuit of the electro-magnet 30 winding 6 being thereupon established, the electrodes 1 and 2 will again be brought into engagement and the feeding of the electrode 1 will occur after which the electrodes will be again separated and the lamp will continue to operate as before.

While the invention has been shown and described as applied to a particular form of lamp, it will, of course, be understood that it may also be applied to lamps that differ in structure and arrangement of the parts and circuits, and other devices than that shown and described may also be employed for causing a lamp to operate in accordance with the invention.

I claim as my invention:

1. In an arc lamp, the combination with normally separated electrodes, and an electro-magnet for causing the same to engage, of a switch arranged in shunt to the electro-magnet winding, the movable member of which is provided with adjustable stops, and an actuating arm carried by the armature or core of said electro-magnet and adapted to engage the stops on said movable switch member.

2. In an arc lamp, the combination with normally separated electrodes and an electro-magnet for causing the same to engage, of a switch arranged in shunt to the electro-magnet winding the movable member of which is provided with adjustable stops, an actuating arm carried by the armature or core of said magnet and adapted to engage the stops on said movable switch member, and means for retaining said movable switch member in any position to which it may be moved.

In testimony whereof, I have hereunto subscribed my name this 28th day of June, 1906.

WILLIAM G. HOUSKEEPER.
